HYDRAULIC DUST CURTAIN

Donald E. Herman, Cedar Rapids, Iowa, assignor to Pettibone Mulliken Corporation, Chicago, Ill., a corporation of Delaware

Filed Dec. 21, 1964, Ser. No. 419,978

5 Claims. (Cl. 241—186)

This invention relates to a hydraulic mechanism comprising an improved device for operating the dust curtains of a hammermill or the like; this disclosure thereof being offered for public dissemination in the event adequate patent protection is granted.

It has long been the practice to provide reversible hammermills with dust curtains and to make the dust curtains jointly shiftable or reversible to assume appropriate positions for each direction of rotation. Reversible hammermills are commonly fed through a chute extending directly upwardly from the highest point of the hammer circle. Viewed in cross section, the entering material such as rock, coal or the like, or the fragments resulting from initial impact with the hammers, will be thrown to the right with clockwise rotation of the rotor or hammers and thrown to the left with counterclockwise rotation. It is, therefore, desirable that the rigidly and permanently located breaker bars in both directions be spaced from the hammer circle to provide a clearance to receive this stream of fragmented material impelled by the hammers. Without such a clearance there would be excessive abrasion and wear, and in some instances, more fines than desired.

When the stream of fractured rock is being thrown through the clearance in one direction from the feed and impact area, unless a dust curtain is moved into position across the opposite or idle clearance, dust will be swept or blown up through it and excessive quantities of dust will escape through the feed chute. The dust curtain preferably extends close to the hammer circle. It is, therefore, necessary to shift, or switch, or reverse the position of the dust curtains each time that the direction of rotation of the hammer rotor is reversed. Heretofore, there has been a variety of mechanical means for reversing the dust curtains. Some have been successful, but none have been really satisfactory and trouble-free. According to the present invention, a hydraulic mechanism is provided for reversing the dust curtains. A hydraulic system not only avoids the exposed linkages or the like which were sometimes the source of trouble, but also lends itself to the development (even though a manual pump is used) of high operating forces when needed. In its preferred form, the hydraulic system, by an exceedingly simple hydraulic scheme, ensures equal motion of all parts of the dust curtains. This equalized movement is important in achieving maximum ease of operation and in being sure that no matter where the dust curtain is located when movement is terminated, its spacing from the hammer circle will be uniform along the length of the dust curtain.

Additional objects and advantages of the invention will be apparent from the following description and from the drawings.

Designation of figures

FIGURE 1 is a fragmentary vertical cross-sectional view generally radial but showing two different planes, of a hammermill embodying the present invention, omitting most of the hydraulic system and showing electrical controls diagrammatically;

FIGURE 2 is a fragmentary view in vertical cross section taken approximately along or broken away to the line 2—2 of FIG. 1;

FIGURE 3 is a diagrammatic illustration showing the hydraulic system;

2

FIGURE 4 is a view showing a modification of one part of the hydraulic system.

Background description

5 Although the following disclosure offered for public dissemination is detailed to ensure adequacy and aid understanding, this is not intended to prejudice that purpose of a patent which is to cover each new inventive concept therein no matter how others may later disguise it by variations in form or additions or further improvements. The claims at the end hereof are intended as the chief aid toward this purpose, as it is these that meet the requirement of pointing out the parts, improvements, or combinations in which the inventive concepts are found.

10 15 The invention has been illustrated in conjunction with a reversible rotary crusher of the hammermill type. The details of this hammermill are not important to this invention, for the most part, and therefore are not described.

20 Rotor 12 carries hammers 13 which are illustrated as mounted on swing arms 14. As the hammers 13 rotate their tips describe a hammer circle 16. Material to be crushed is fed through feed chute 17. As it is struck by hammers 13 it is usually fractured and is thrown

they are found, blocking the flow of oil from all cylinders. Its other positions will either raise dust curtain 21 and lower dust curtain 22 or vice versa. The preferred hydraulic circuit is a single series circuit described further below which has the advantage of ensuring equalized parallel movement of the two dust curtains, or all four ends moving equally.

As seen in FIG. 1, piston rods 24 and 28 carry actuators 46, which may be adjustable as shown, for tripping switches 47. These switches 47 are connected to the motor control relay box 48 which includes reversing controls for motor 49 which is the drive motor for rotor 12. When dust curtain 21 is raised, its associated switch 47 automatically controls the motor control 48 to cause rotation to be normally in the counterclockwise direction. When dust curtain 22 is raised, its associated switch 47 controls motor control box 48 to cause the motor 49 to drive rotor 12 normally in the clockwise direction. Preferably, if neither switch 47 is actuated by a raised dust curtain, the motor control unit 48 will not permit normal drive of the rotor 12 in either direction. Of course, there may be overriding manual control so that when desired, as for repair, the rotor 12 can be turned or inched in either direction at any time.

Hydraulic circuitry

The first installation of hydraulic dust curtains used a more ordinary hydraulic circuit than that shown in FIG. 3, and was found to be troublesome in its failure to maintain parallel movement of the dust curtains. Various means for obtaining parallel movement were considered, but for reasons such as cost, none seemed quite satisfactory until the problem was solved by the hydraulic circuit shown in FIG. 3. The illustrated form of series hydraulic circuit solved the problem completely.

When the concept of a series hydraulic circuit was first considered, it was discarded because of the unequal effective cross sections of the two ends of ordinary hydraulic cylinders, meaning, of course, the hydraulic cylinder and piston combination. Thus, referring to cylinder 36 in FIG. 3, it is apparent that above the piston 36' the effective area of the piston or of the cylinder is the full horizontal cross-sectional area of the cylinder 36. Below the piston 36', however, the effective area is reduced by the cross-sectional area of the piston rod 37. It follows an attempt to move both ends of dust curtain 21 equally by a series circuit, considering its two cylinders only, would fail. Thus, if pump pressure should be applied below piston 36' to raise that end of the dust curtain 21, and the upper end of cylinder 36 connected to the lower end of cylinder 23 to raise that end of dust curtain 21, the unequal cross sections above piston 36' and below piston 23' would cause piston 23' to be raised faster than piston 36'.

According to the present invention, however, all inter-cylinder connections are to cylinder ends of equal effective cross section. Thus, if a valve control line 51 is connected from the valve port to the upper end of cylinder 31, the lower end of cylinder 31 will be connected not to cylinder 27 but to the lower end of cylinder 36. Now the piston 36' will be raised the same amount that the piston 31' is lowered. The upper end of cylinder 36 is connected to the upper end of cylinder 27, both being a full cross section. Therefore, piston 27' will be lowered the same amount that piston 36' is raised and hence the same amount that piston 31' is lowered. The lower end of cylinder 27 is connected to the lower end of cylinder 23, and thus its piston 23' will be moved the same amount as the other three pistons. The other valve control line 52 is connected to the upper end of cylinder 23.

It would usually be desirable to have the pump and valve unit 41, 43 located considerably below the cylinders. In that event, there will be a tendency for the hydraulic fluid in line 51 or 52 to run out if the conventional fully open return connection is provided through valve 43. Ac-

cordingly, relief valve 61 has been provided in the return line from valve 43 to tank 42. This is a low pressure relief valve having the purpose of merely maintaining above it enough pressure to overcome the gravitational pressure of the oil in line 51 or line 52. A pressure valve maintaining 65 pounds per square inch has been chosen because of ready commercial availability and to provide a safe margin. Commercial units including pump 41, valve 43 and tank 42 conventionally include a high pressure relief valve 62. The pump 41 is capable of producing high pressure, even though manual, and a relief valve 62 which limits the line pressure to 2,000 pounds per square inch is deemed suitable and desirable. In one commercial embodiment, 400 pounds per square inch seems adequate, and hence the 2,000 pounds is expected to overcome any increased friction or binding by particles.

It is desirable that all air be eliminated from the hydraulic system. The conventional bleed plugs 70 are an aid to this end. However, a bleed reservoir 71 is preferably connected to the uppermost point of every inter-cylinder hydraulic line, the bottom of the reservoir being higher than any point it supplies. Each is connected through a valve 72 which will normally be kept closed so that the system will function as if the bleed reservoir 71 were not present. During installation, however, or whenever the presence of air is suspected, the appropriate valve 72 can be opened allowing any air which has accumulated below the valve to flow up into bleed reservoir 71, being replaced by oil from that reservoir. During installation, before the dust curtains are installed, air is bled repeatedly while alternate pistons are held up to allow the right amount of oil to enter. After installation, if bleeding is necessary, the right amount of oil can still be allowed to enter by raising the dust curtain which is too low. If this proves necessary unexpectedly often, each reservoir may be provided with a valve nipple 73 through which air or oil may be inserted into the reservoir to hold the raised piston at the proper level until valve 72 is closed. Instead of reservoirs 71, there may be simple bleed valves with provision for connecting temporarily a source of oil under pressure.

FIG. 4 shows a modification of the hydraulic circuit which is possible because the contents of the hydraulic circuit are constant insofar as operation is concerned. Here the pump 41 is connected between the ports of the valve, no sump tank in the usual sense being provided. To maintain a pressure in the discharge line safely, a small reservoir 81 may be provided at a level above all cylinders. This reservoir will also take care of expansion of oil in the system. It is only with this system that reservoirs 71 may be needed for lines 51 and 52; and probably they will not be needed then if reservoir 81 is provided.

Pump 41 preferably uses a small piston suitable for developing 10,000 pounds pressure per square inch by manual operation. This makes operation at the expected 2,000 pounds per square inch very easy. More important, it facilitates delicate adjustment of the position of the lower dust curtain, a full stroke only moving it about one thirty-second of an inch. Nevertheless, the entire pumping operation takes only around half a minute.

Further details

Some operators will prefer to adjust actuators 46 to actuate switches 47 only as the dust curtain being lowered reaches its desired position. Other operators will prefer an adjustment actuating switches 47 enough earlier so that actuators 46 will never need adjustment, but will actuate switches 47 by the time the lowering dust curtain reaches any of the positions that may be desired. For the latter, switches 47 should tolerate further movement after they have been actuated.

It may be desirable to provide at one or more intermediate points along the length of dust curtains 21 and 22, clamps 86, as seen in FIGS. 1 and 2. Each clamp may

have welded to it a spacer heel 7 and a bolt 88. The clamps may be held in proper position by guide strips 89 welded to the adjacent wall member. The nuts on bolt 88 may be more accessible if a spacer 91 is provided. It will usually be preferred to adjust the nuts so that dust curtains 21 and 22 can slide smoothly and easily, but if objectionable rattles should develop the nuts may be taken up after each reversal of the dust curtains to stop such rattle.

The dust curtains may have the simple construction seen in FIG. 2, in which a tie plate 92 is welded to each end of the main horizontally extending section of the dust curtain each being secured by bolts 93 to an end plate 94, these end plates bearing the ears 29 and 33. This facilitates assembly and also permits ready replacement of the main portions of the dust curtains which may wear fastest.

Customary side liners 96 provided within the housing of the hammermill 11 at the ends of the rotor may be shaped to form slots 97 into which each dust curtain slides. The seat of this slot could serve as a stop for the movement of the dust curtain toward the hammer circle. However, it is preferred that this slot extend somewhat too deeply for new unworn hammers, and hence the positioning of the dust curtains will usually be chosen by the operator. Of course, he will choose a position which is not struck by the hammers, but which is close enough to the hammer circle to accomplish the desired or achievable reduction of escape of dust. Turnbuckles or threaded adjustable tubes 98 may be provided between the piston rods 24, etc., and clevises 99 which are pivoted to ears 26, etc., to adjust the lowest length to which the dust curtains will extend. This is believed not to be necessary, however, in view of the ease of obtaining accurate positioning of the dust curtains by the hydraulic system of this invention.

With this invention, the reversing of the positions of the dust curtains is accomplished very easily, and they can be very accurately positioned. Enough force is available for very dependably and easily overcoming any jamming which may occur from lodged particles of the material being crushed.

What is claimed is:

1. Apparatus for reversing the positions of two dust curtains on reversible hammermills and the like including four double-acting hydraulic cylinders with pistons, and piston rods extending in one direction only from the pistons and reducing the effective cross-sectional area of the cylinders in that direction from the pistons; each linked to a different one of the four end portions of the two dust curtains; a hydraulic pump, and a three-position valve and conduits for at will supplying pump pressure above the pistons of one dust curtain and below the pistons of the other dust curtain, or vice versa, or locking the pistons in their given positions by blocking all flow from the cylinders; said valve being connected to said cylinders in a series circuit with each intercylinder connection being between cylinder ends of the same effective cross-sectional area whereby all pistons move equally.

2. Apparatus for reversing the positions of two dust curtains on reversible hammermills and the like including four double-acting hydraulic cylinders with pistons, and piston rods extending in one direction only from the pistons and reducing the effective cross-sectional area of the cylinder in that direction from the pistons; each linked to a different one of the four end portions of the two dust

- curtains; a hydraulic pump, and a three-position valve and conduits for at will supplying pump pressure above the pistons of one dust curtain and below the pistons of the other dust curtain, or vice versa, or locking the pistons in their given positions by blocking all flow from the cylinders; said valve being connected to said cylinders by a series hydraulic circuit extending from a pressure port of the valve to a given side of cylinder one connected to dust curtain A, from the same cylinder on the opposite side of the piston to the like end of cylinder two connected to dust curtain B, from cylinder two on the opposite side of its piston to a like end of cylinder three, connected to dust curtain A, from the opposite end of cylinder three to the like end of cylinder four connected to dust curtain B, and from the opposite end of cylinder four to the return port of the valve.
3. Apparatus for reversing the positions of two dust curtains on reversible hammermills and the like including four double-acting hydraulic cylinders with pistons, each linked to a different one of the four end portions of the two dust curtains, a hydraulic pump, and a three-position valve and conduits for at will supplying pump pressure above the pistons of one dust curtain and below the pistons of the other dust curtain, or vice versa, or locking the pistons in their given positions by blocking all flow from the cylinders; said valve being connected to said cylinders in a series circuit with each intercylinder connection being between cylinder ends of the same effective cross-sectional area whereby all pistons move equally.
4. Apparatus for reversing the positions of two dust curtains of reversible hammermills and the like including four double-acting hydraulic cylinders with pistons, each linked to a different one of the four end portions of the two dust curtains; and a hydraulic system for actuating said cylinders including hydraulic pump means, and a three-position valve and conduits for at will supplying pump pressure above the pistons of one dust curtain and below the pistons of the other dust curtain or vice versa, or locking the pistons in their given positions by blocking all flow from the cylinders, said hydraulic system including means to cause each dust curtain to move with parallel movement.
5. Apparatus for reversing the pistons of two dust curtains on reversible hammermills and the like including four double-acting hydraulic cylinders with pistons, each linked to a different one of the four end portions of the two dust curtains, hydraulic pump means, and a three-position valve and conduits for at will supplying pump pressure above the pistons of one dust curtain and below the pistons of the other dust curtain, or vice versa, or locking the pistons in their given positions by blocking all flow from the cylinders, said apparatus including means for ensuring for each dust curtain, when lowered, proper angularity as to the hammermill.
